E. J. EVANS,

RAILWAY SIGNAL.

APPLICATION FILED FEB. 28, 1920.

1,352,801.

Patented Sept. 14, 1920.

UNITED STATES PATENT OFFICE.

FREDERICK JOHN EVANS, OF BARRY, WALES.

RAILWAY-SIGNAL.

1,352,801.

Specification of Letters Patent. Patented Sept. 14, 1920.

Application filed February 28, 1920. Serial No. 362,011.

To all whom it may concern:

Be it known that I, FREDERICK JOHN EVANS, a subject of the King of Great Britain, residing at 2 Gaspard Place, Barry, in the county of Glamorgan, Wales, Great Britain, have invented new and useful Improvements in Railway-Signals, of which the following is a specification.

This invention relates to improvements in railway and the like signals and apparatus, and more especially to signals for indicating automatically to a driver the position of railway points.

The object of this invention is to provide a signal which shall definitely indicate whether the points are open or closed. When railway points are operated from a signal cabin at a distance from them, the points may remain open, although the operator in the signal cabin has moved the lever to the closed position; this has been the cause of accidents. By my invention this defect has been overcome.

According to my invention a signal is set at "danger" or at "clear" by the points, the arrangement being such that except when the points are substantially closed, the signal is at "danger."

In practice the arrangement may conveniently be so set that the signal is at danger when the points are a greater distance than $\frac{3}{8}$ of an inch from their closed position.

Preferably the signal is actuated by a tumbler or snap action in such a manner that a very small movement of the points, when near their closed position, sets the signal definitely either at "clear" or at "danger."

The drawings show diagrammatically how the invention may be carried out.

Figure 1 is a general view, Fig. 2 is an end elevation partly in section, Fig. 3 is a detail in plan, Fig. 4 shows a modification and Fig. 5 a plan of the actuating rod.

A is a disk signal rotatably mounted on a boss B on a casing C; D is a bell crank lever pivotally mounted on a boss E on the casing C; the end of one arm is connected by a rod F to the signal A, while the end of the other arm is connected by a spring G to a lever H mounted on a shaft J. K is a counterweight tending to keep the lever H in a vertical position. L is a slotted rod connected to a point M, and adapted to engage with the lever H; N is a rail; O and P

are red and green glasses carried by the signal A; R are stops to limit the movement of the lever D.

In operation, when the point M comes within say $\frac{3}{8}$ of an inch of the rail N, the rod L comes in contact with and tilts the lever H. As soon as the spring G has been moved past the pivot of the bell crank lever D, the bell crank lever D and connecting rod F are quickly moved to the position shown in dotted lines in Fig. 1, and the signal A is set at "clear". Conversely when the points are opened, as soon as the point M has moved a short distance, the spring G is moved past the pivot of the bell crank lever D and the signal A is moved quickly to danger and remains at danger whatever farther distance the point M may be moved away from the rail N.

When it is desired to operate the signal A at a distance from the point M, the rod J is prolonged as shown in Fig. 4, and a second lever S, to which the spring G is attached, is secured to it.

It will be seen that with the arrangement described the condition of the points is definitely indicated to a driver without the aid of a signal cabin, and that the signal is not moved until the points have reached a certain definite position.

What I claim is:—

1. The combination of a railway signal, points, and a snap action lever so connecting the said signal to the points that the signal is at danger except when the points are substantially closed.

2. The combination of a railway signal, points, and a snap action lever so connecting the said signal to the points that a small movement of the points causes the full movement of the signal.

3. The combination of a railway signal, points, an oscillating lever operated by the points, and means connecting the oscillating lever to the signal whereby a small movement of the oscillating lever causes the full movement of the signal.

4. The combination of a railway signal, points, an oscillating lever operated by the points, a bell crank lever, one of whose arms is connected to said signal, and means connecting the other arm of the bell crank to the oscillating lever whereby a small movement of the oscillating lever causes the full movement of the signal.

5. The combination of a railway signal,

points, an oscillating lever operated by the points, a bell crank lever, one of whose arms is connected to said signal, and a spring connecting the other arm of the bell crank to the oscillating lever whereby a small movement of the oscillating lever causes the full movement of the signal.

6. The combination of a railway signal, points, an oscillating lever, a slotted rod connected to said points and engaging said oscillating lever and means connecting the oscillating lever to the signal whereby a small movement of the oscillating lever causes the full movement of the signal.

15 7. The combination of a railway signal, points, an oscillating lever, a slotted rod connected to said points and engaging said oscillating lever, a bell crank lever, one of whose arms is connected to said signal, and means connecting the other arm of the bell crank to the oscillating lever whereby a small movement of the oscillating lever causes the full movement of the signal.

8. The combination of a railway signal, points, an oscillating lever, a slotted rod connected to said points and engaging said oscillating lever, a bell crank lever, one of whose arms is connected to said signal, and a spring connecting the other arm of the bell crank to the oscillating lever whereby a small movement of the oscillating lever causes the full movement of the signal.

9. The combination of a railway signal, points, and a snap action lever so connecting the said signal to the points that a small movement of the points causes the full movement of the signal.

10. The combination of a railway signal, stops to limit the movement of the signal, points, an oscillating lever operated by the points, and means connecting the oscillating lever to the signal whereby a small movement of the oscillating lever causes the full movement of the signal.

11. The combination of a railway signal, stops to limit the movement of the signal, points, an oscillating lever operated by the points, a bell crank lever, one of whose arms is connected to said signal, and means connecting the other arm of the bell crank to the oscillating lever whereby a small movement of the oscillating lever causes the full movement of the signal.

12. The combination of a railway signal, stops to limit the movement of the signal, points, an oscillating lever operated by the points, a bell crank lever, one of whose arms is connected to said signal, and a spring connecting the other arm of the bell crank to the oscillating lever whereby a small movement of the oscillating lever causes the full movement of the signal.

13. The combination of a railway signal, 65 stops to limit the movement of the signal,

points, an oscillating lever, a slotted rod connected to said points and engaging said oscillating lever, and means connecting the oscillating lever to the signal whereby a small movement of the oscillating lever causes the full movement of the signal.

14. The combination of a railway signal, stops to limit the movement of the signal, points, an oscillating lever, a slotted rod connected to said points and engaging said oscillating lever, a bell crank lever, one of whose arms is connected to said signal, and means connecting the other arm of the bell crank to the oscillating lever whereby a small movement of the oscillating lever causes the full movement of the signal.

15. The combination of a railway signal, stops to limit the movement of the signal, points, an oscillating lever, a slotted rod connected to said points and engaging said oscillating lever, a bell crank lever, one of whose arms is connected to said signal, and a spring connecting the other arm of the bell crank to the oscillating lever whereby a small movement of the oscillating lever causes the full movement of the signal.

16. The combination of a railway signal, points, a rod, an oscillating lever mounted in said rod and operated by the points, a bell crank lever, one of whose arms is connected to said signal, and means connecting the other arm of the bell crank to a lever fast with the rod on which said oscillating lever is mounted whereby a small movement of the oscillating lever causes the full movement of the signal.

17. The combination of a railway signal, points, a rod, an oscillating lever mounted on said rod and operated by the points, a bell crank lever, one of whose arms is connected to said signal, and a spring connecting the other arm of the bell crank to a lever fast with the rod on which said oscillating lever is mounted whereby a small movement of the oscillating lever causes the full movement of the signal.

18. The combination of a railway signal, stops to limit the movement of said signal, points, a rod, an oscillating lever mounted on said rod and operated by the points, a slotted rod connected to said points and engaging said oscillating lever, a bell crank lever, one of whose arms is connected to said signal, and a spring connecting the other arm of the bell crank to the oscillating lever whereby a small movement of the oscillating lever causes the full movement of the signal.

19. The combination of a railway signal, points, an oscillating lever operated by the points, means adapted to return the oscillating lever to its normal position, and means connecting the oscillating lever to the signal whereby a small movement of the oscillating lever causes the full movement of the signal.

20. The combination of a railway signal,

points, an oscillating lever operated by the points, a counterweight on the oscillating lever, and means connecting the oscillating lever to the signal whereby a small movement 5 of the oscillating lever causes the full movement of the signal.

21. The combination of a railway signal, points, an oscillating lever operated by the points, means adapted to return the oscillating lever to its normal position, a bell crank lever, one of whose arms is connected to said signal, and means connecting the other arm 10 of the bell crank to the oscillating lever whereby a small movement of the oscillating lever causes the full movement of the signal.

22. The combination of a railway signal, stops to limit the movement of the signal, points, an oscillating lever operated by the points, means adapted to return the oscillating lever to its normal position, and means 15

connecting the oscillating lever to the signal whereby a small movement of the oscillating lever causes the full movement of the signal.

25

23. The combination of a railway signal, points, a rod, an oscillating lever mounted on said rod and operated by the points, means adapted to return the oscillating lever to its normal position, a bell crank lever, one 30 of whose arms is connected to said signal, a lever fast with the rod on which said oscillating lever is mounted and means connecting the other arm of the bell crank to said last mentioned lever whereby a small movement 35 of the oscillating lever causes the full movement of the signal.

In testimony that I claim the foregoing as my invention, I have signed my name this 6th day of February 1920.

FREDERICK JOHN EVANS,
